UNITED STATES PATENT OFFICE.

FRITZ SCHWARZER, OF ST. GALLEN, SWITZERLAND.

SIGNAL-WHISTLE.

1,322,205.

Specification of Letters Patent. Patented Nov. 18, 1919.

Application filed December 31, 1918. Serial No. 269,110.

To all whom it may concern:

Be it known that I, FRITZ SCHWARZER, a citizen of the Swiss Confederation, and residing at St. Gallen, Switzerland, have invented certain new and useful Improvements in Signal-Whistles, of which the following is a specification.

The present invention has reference to certain new and useful improvements in alarm or signal whistles, and relates more particularly to whistles actuated by a suitable power fluid, as for instance a jet of steam or the explosion or exhaust gases of a motor, and the invention has for its specific object to provide means whereby the sounding member to be impinged upon by the pressure medium can be swung around on the valve casing proper, as can also the head part of the device which comprises the valve actuating mechanism, for the purpose to allow of mounting such an alarm device even in places where a one-piece or rigidly assembled alarm device could be set up only under great difficulties or not at all, so that the sounding member and the valve operating mechanism can be directed, independently of one another, to any point of the compass without the supporting valve casing being likewise rotated.

My invention will best be understood when described in connection with the accompanying drawings, in which Figure 1 is a side elevation of the alarm whistle, partly in section; Fig. 2 is a plan view, and Fig. 3 a horizontal section therethrough on line A—B of Fig. 1.

The device essentially comprises the valve casing with axially operable valve stem, the rotatable valve jacket with the sounding member rigidly secured thereto, and the rotatable valve operating mechanism.

The valve casing consists of the centrally bored shell or stem 1, whose lower extremity is provided with an external thread 2 and whose upper end is preferably in the shape of a hexagon head 3 with an integral annular neck portion 8. About its middle the wall of this shell is pierced by radially disposed ports 4. As shown in Fig. 3 there are provided four such ports, but it is to be understood that also a lesser number may be arranged. The lower mouth of the shell forms the seat 5 for the valve disk 6 of the long valve stem 7 extending clear through the valve casing to beyond the annulus 8. Between the valve stem 7 and the

wall of the casing 1 there is provided in the lower portion of the latter an annular chamber 9. The valve jacket 10 above and below snugly surrounds the valve casing 1 and provides between it and the latter an annular chamber 11. At one side there extends laterally from this rotatable jacket 10 a cup-shaped member 12, and the jacket wall within this cup presents a thickened center boss 13 and a plurality of ports 14. Into the boss 13 is screwed the one end of a stud 15, to the other end of which is suitably secured the closed end of the sounding member 16 with the aid of the counter nuts 17. Within the cup member 12 is positioned on the stud 15 a disk 18 of such dimensions that between it and the dish wall a fine circular slot or port 19 is presented, and the thin facing edge 20 of the contracted throat of the sounding member is designed to properly register therewith, as well known in the art.

Upon the hexagon head 3 and annulus 8 is rotatably positioned the valve actuating mechanism, comprising an essentially U-shaped chair 21, in the one leg 21' of which is fulcrumed the one end of a pull-lever 22 to the free end of which is attached a pull member 24, which is preferably a so-called Bowden cable, that is a wire core about which a wire spiral is closely wound. The wire core 25 passes freely through the small bore 26 in the leg 21'' of the chair 21 and the spiral mantle 27 is accommodated in the larger bore 28 thereof. A spring ring 29 prevents the lever chair 21 from becoming inadvertently detached. Between the valve jacket and the hexagon there is provided a packing 30.

The upper extremity of the valve stem is rounded-off and is positioned underneath the pull-lever 22, and it rests on the washer 31, between which latter and the chair 21 a helical compression spring 32 is interposed.

In mounting such an alarm whistle, its threaded lower end 2 is screwed home into the pressure carrying pipe, the whistle member proper and its actuating mechanism not being rotated the while, which is often very convenient when working in cramped quarters, where the laterally extending sounding cup could not be swung around in a circle. As soon as the parts are screwed together far enough so that the pressure pipe contacts with the lower edge of the valve jacket 10, the latter with its sounding member is

swung into the desired horizontal position and the parts are then tightened-up definitely. Finally the valve stem operating mechanism is relatively rotated until the 5 cable is in the desired position free from interference with the sounding member and other obstructions.

For blowing the whistle, the cable is pulled and the lever 22 consequently depressed to operate the valve stem, which lifts the valve head off its seat, when the pressure medium, for instance the exhaust from an engine cylinder, can pass into the chamber 9, from there through the ports 4 5 into the chamber 11, then through the ports 14 and the annular port 19 to impinge on the facing edge 20 of the sounding member 16. On release of the cable, the valve will 0 be closed by the action of the expanding spring 32.

What I claim is:—

1. In an alarm device of the character described, in combination, a valve casing, a chamber jacket, a sounding member on 5 said jacket, a valve in said casing, and means for operating said valve; said jacket and said valve operating means being mounted on said casing with capability of independent relative rotation, for the purpose of arranging the jacket with its sounding member and the valve operating means, independently of one another, in the most favorable operative position, no matter what the relative position of the supporting valve 0 casing.

2. In an alarm device of the character described, in combination, a valve casing, a chambered jacket mounted on said casing with capability of temporary relative rotation, a sounding member extending laterally from said jacket, a valve operable within said valve casing, and means for operating said valve.

3. In an alarm device of the character described, in combination, a valve casing, a chambered jacket mounted on said casing with capability of relative rotation, a sounding member extending laterally from said jacket in rigid connection therewith, a valve operable within said casing and controlling the flow of pressure medium through said casing and said jacket and onto said

sounding member, and means for operating said valve, mounted on said casing with capability of relative rotation, independently of that of said jacket. 55

4. In an alarm device of the character described, in combination, a valve casing having lateral ports, means for operatively connecting said valve casing to a pressure conduit, a stemmed valve operable in said casing, the walls of said casing and the stem of said valve presenting between them an annular chamber closed above and adapted to be placed in communication with the 60 pressure conduit upon actuation of said valve, means for operating said valve, a jacket surrounding part of said valve casing in such manner that an annular, top-and-bottom-closed chamber is formed therebetween, a cup-shaped member extending laterally from said jacket in communication with the second said annular chamber, a concentric baffle member in said cup member of such dimensions that an annular port 65 is formed between it and the cup member, a sounding member whose free edge is in operative register with said annular port, the said valve jacket being mounted on said valve casing with capability of relative rotation and designed to be clamped in the 70 relative end position by the valve casing being connected to the pressure conduit.

5. In an alarm device of the character set forth, in combination, a valve casing, a 85 sounding member mounted on said casing with capability of relative rotary displacement and in operative communication therewith, means for locking said sounding member in its adjusted relative position, a spring 90 actuated valve operable in said casing, and means for operating said valve, comprising a substantially U-shaped seat member mounted on said valve casing with capability of relative rotation, lever means pivotally secured to one leg of said U-member and adapted to actuate said valve, and a Bowden cable attached to the free end of said valve actuating lever and its core 95 passing freely through the other U-member leg and its envelop abutting thereagainst. 100

FRITZ SCHWARZER.
